EMBLEM PLATE OR SIMILAR ARTICLE

Samuel Simonelli, Flora, Ill.

Application August 20, 1954, Serial No. 31,955

Term of patent 7 years

(Cl. D29—2)

FIG. 1

To all whom it may concern:

Be it known that I, Samuel Simonelli, a citizen of the United States, residing at Flora, in the county of Clay and State of Illinois, have invented a new, original, and ornamental Design for an Emblem Plate or Similar Article, of which the following is a specification, reference being had to the accompanying drawing, forming a part hereof.

Figure 1 is a top plan view of an emblem plate or similar article showing my new design; and

I claim:

The ornamental design for an emblem plate or similar article, as shown.
